TOOTHBRUSH HEAD FOR AN AEROSOL DENTIFRICE DISPENSER

Daniel H. Gattone, 4409 Dermon Ave., Drexel Hill, Pa.

Filed Oct. 23, 1964, Ser. No. 82,300

Term of patent 14 years

(Cl. D9—2)

FIG. 1.

FIG. 2.

FIG. 3.

FIG. 4.

FIGURE 1 is a top plan view of a toothbrush head for an aerosol dentifrice dispenser, showing my new design;

FIGURE 2 is a side elevational view thereof;
FIGURE 3 is a front elevational view thereof; and
FIGURE 4 is a rear elevational view thereof.

The broken line showing of the body of the dispenser is for illustrative purposes only.

I claim:

The ornamental design for a toothbrush head for an aerosol dentifrice dispenser, as shown and described.
